UNITED STATES PATENT OFFICE.

ORA DRAKE, OF CLEVELAND, OHIO.

DESIGN FOR A SHOE FOR VACUUM CLEANING-MACHINES.

46,631.

Specification for Design.

Patented Nov. 10, 1914.

Application filed August 4, 1913. Serial No. 782,952. Term of patent 7 years.

To all whom it may concern:

Be it known that I, ORA DRAKE, a citizen of the United States, residing at Cleveland, in the county of Cuyahoga and State of Ohio, have invented a new, original, and ornamental Design for a Shoe for Vacuum Cleaning-Machines, of which the following is a specification, reference being had to the accompanying drawing, forming part thereof.

Figure 1 is a top plan view, Fig. 2 is a bottom plan view, of a shoe for vacuum cleaning machines showing my new design.

I claim:

The ornamental design for a shoe for vacuum cleaning machines, as shown.

ORA DRAKE.

Witnesses:

M. M. BUTCHER,
H. A. WARD.
